CLARENCE RAND, OF AUBURN, MAINE.

RING-ADJUSTING MACHINE FOR BOBBINS.

Application filed May 25, 1926. Serial No. 111,501.

A large proportion of the shuttle bobbins in common use are fitted with one or more rings of tempered steel wire which are kept in place by spring tightness. It is usually necessary for satisfactory working, to adjust the open joints of each of these rings to a definite predetermined position.

The object of my invention is to provide a machine which can be readily adapted to adjusting the position of these joints in a great variety of bobbins or other rings supporting pieces.

The construction shown in the accompanying drawings is especially designed for adjusting the joints of the three rings of a certain bobbin at equal distances from each other; but it is readily adaptable, without changing its mode of operation, to adjusting the joints in any other definite relation to each other or to any bobbin or other central support with which the rings make frictional contact. In the accompanying drawings Fig. 1 is a full size drawing, in partial section, showing the bobbin with its attached and unadjusted rings, and the parts which act directly on the rings; Fig. 2 and Fig. 3 are details of Fig. 1; Fig. 4 is a front elevation of the complete machine; Fig. 5 is a detail of Fig. 4; Fig. 6 is a plan of the bobbin feeding mechanism of Fig. 4 with a part cut away to show its internal structure; Fig. 7 is a rear elevation of the ring adjusting mechanism; Fig. 8 is a sectional plan through the line $x-y$ of Fig. 7; Fig. 9 is a similar plan showing details just below the line $a-b$ of Fig. 7; Figs. 10, 11, 12, 13, taken together, show the interactions and time relations of the four cams on the principal shaft.

40 In each of these figures a division of the circumference into six corresponding parts is similarly indicated as, S^1 , S^2 , S^3 , S^4 , S^5 , S^6 .

Fig. 10 shows the cam which imparts a back and forth motion to the parts which adjust the position of the ring joints.

Fig. 11 shows the cam which controls the final position of the ring joints that are first adjusted.

50 Fig. 12 shows the cam which controls the final position of the ring joint or joints that are last adjusted.

Fig. 13 shows the cam that actuates the parts that disconnect the ring adjusting mechanism from the ring joints and hold it locked until the bobbin is shifted.

Fig. 14 is a detail drawing of the parts which act directly on the bobbin rings.

In these drawings A is any part of the fixed framework, B is a bobbin, 1, 2, 3 are the open joints in the rings on the bobbin, 4, 5, 6 are catches which are pressed into the joints 1, 2, 3 by the springs 7, 8, 9. These catches and pins are identical in shape and function. The catches 5, 6 and corresponding springs 8, 9 are not shown in the drawings; but their positions are sufficiently indicated by the holes 15, 16, which pass through them. 10, 11, 12 are ring enclosing gears which are themselves inclosed and kept in place by the case 13; 14, 15, 16 are holes which pass through the catches 4, 5, 6 and through the adjacent gears 10, 11, 12; 17, 18, 19 are wedge pointed pins which pass through the holes 14, 15, 16 and pull the 75 catches out of the open joints 1, 2, 3; the cam 20, through the rockshaft 21, imparts an upward and downward motion to the guided frame 22 on which are mounted the wedge pointed pins 17, 18, 19; 23, 24, 25 are 80 driving gears which mesh with the inclosing gears 10, 11, 12; 26 is a gear on the shaft of 24 which meshes with a similar gear 77 on the shaft of 23; on the shaft 27 of 24 are mounted the single notched ratchet wheel 28, the loose gear 29 (connected with 28 by the pawl 38) and the adjusting and locking cam 30 that is controlled by the swinging arm 31 which receives its motion through the connecting rod 33 from the cam 34; the shaft 35 of the driving gear 25 carries the single notched ratchet wheel 36 connected with the loose gear 37 by the pawl 39; the shaft 35 also carries underneath the fixed 85 supporting plate A, the adjusting and locking cam 40 that is controlled by the swinging arm 41 which receives its motion through the connecting rod 42 and the rocking arm 43 from the cam 44; the loose gears 29 and 37 are in mesh with the rack 45 which receives its motion through the rocking arm 46 from the cam 47 which forms part of the driving gear on the cam shaft 48, this gear 47 is in mesh with the pinion 49 on the driving shaft 50; on this driving shaft 50 is a 90 worm 51 which engages a worm gear 52 on the vertical shaft 53; the worm and gear (51 and 52) are so proportioned that the revolutions of the cam shaft 48 and the vertical shaft 53 are identical; at the top of the vertical shaft 53 is the one-leaved-pinion 54 which both drives and locks the duplex gear 95 100 105 110

55. The gear 55 is attached to the under side of the bobbin holder supporting frame 56 which has a series of bobbin holders as 70 fastened to its outer rim and held clear 5 from the fixed plate 57 on which the bobbins rest. In the plate 57 is an opening 58 over the bobbin tube 59 through which the bobbin falls until it strikes the movable stop 60 as shown in Fig. 1; this stop 60 is adjusted to bring 10 the ring joints 1, 2, 3 opposite the gears 10, 11, 12; it varies in shape and vertical position to correspond with different bobbins, or with other ring holding pieces. It receives its motion through a connecting rod 15 from the vertically adjustable cam 61 on the shaft 53. A cam 62 on the same shaft controls the opening and closing of a three leaved chuck 64 through the connecting rod 65 as shown in Fig. 5. The cam 62 is fitted 20 with a yielding channel wall 71 pressed inward by the spring 72. When I wish to make use of my invention I set the machine in motion and bring the cams 47, 34, 44, 20 and their connections approximately into 25 the position shown in Figs. 10, 11, 12, 13, so that the part of the cam opposite S¹ in each of these figures is acting on the cam rollers of the corresponding lever arms 46, 33, 43, 21. Then I drop one or more bobbins 30 into the bobbin holders 70 of the bobbin supporting frame 56 and again set the machine in motion. The single leaf of the pinion 54 enters the corresponding slot in the gear 55 and moves it the definite amount needed to 35 bring the nearest bobbin precisely over the opening 58. The circular part of 54 now enters its circular seat in the rim of 55 which it holds locked through the remainder of the revolution of the cam shafts. 40 As soon as the bobbin holder 70 is in line with 59, the bobbin B drops until it strikes the movable stop 60. As soon as the bobbin drops into place, the cam 62 on the shaft 53 comes into action and closes the centering 45 chuck 64. The construction of this chuck is not shown in detail, as any centering device can be substituted, except that for use on varnished or other finely finished bobbins the jaws should be very smooth. 50 The previously explained construction of the cam 62 makes the centering of the chuck 64 self adjusting for different bobbins, and also permits making the grip of the chuck on the bobbin as light, or as strong as 55 desired. At the time the bobbin drops from the bobbin holder the catches 4, 5, 6 are held pressed back into the gears 10, 11, 12 by the the wedge pointed pins 17, 18, 19, which also hold the catches at the precise points at 60 which the joints 1, 2, 3 are to be placed. As soon as the bobbin has dropped into place the action of the cam 20 removes the pins from the catches, thereby leaving each catch 65 free to be pressed against the ring in front of it by the two compressed springs, as

shown in Figs. 1, 2, and 3. At the same time the adjusting and locking cam 30, which controls the ring inclosing gears 10 and 12, is released by the swinging out of the arm 31. 70

The gears 10 and 12 are now set in motion in opposite directions by the cam 47 acting through the rack 45 and the intermediate gearing specified. As the tempered steel rings usually cling tightly to the bobbins, 75 the catches 4 and 6 slip over them until they are caught in the open joints. They then drag the rings along with them, so that at the end of the traverse of the rack 45 the joints 1, 2, 3 are close to the starting points 80 of the catches 4, 5, 6; when the swinging arm 31, controlled by the cam 34, moving into the notch in the adjusting and locking cam 30, brings it accurately into position and locks it there. 85

Meanwhile, the adjusting and locking cam 40 is released by the swinging out of the arm 41, leaving the gear 11 to be held in place by the friction of the adjustable clamp 75 on the shaft of its driving gear 24 until the locking of the cam 30 and the reversal of the motion of the rack 45, when the single notched ratchet wheel 36 will be in such a position that the pawl 39 will immediately seize it and transmit the motion 90 of the rack 45 to the ring inclosing gears 11 and thereby pull the ring joint 2 round to the starting point of the catch 5. 95

The holes in the inclosing gears will now 100 be in line with the wedge pointed pins on the guided frame 22, which will now be lifted by the cam 20, wedging back the catches 4, 5, and 6.

At the same time the stop 60 is moved out 105 of 59 by the cam 61, the bobbin B drops clear of the machine and another bobbin is moved forward. The machine can be readily adapted to handling a great variety of bobbins and other ringholding pieces by changing the spacing of the wedge pointed pins 110 and the timing of the cams.

Having now fully described the essential features of my invention and their embodiment in a useful machine; what I claim is:

1. In a machine for adjusting a bobbin ring to a definite position, a gear having a central opening concentric with the ring and inclosing it, a case inclosing the gear and keeping it in working position, a spring catch reacting against the gear and entering the open joint in the ring, means of imparting to the gear a series of complete revolutions separated by periods of rest, and means of pulling back the spring catch while the gear is at rest; all in combination with each other and with an internal support for the ring with which it makes frictional contact. 115

2. In a machine for adjusting bobbin rings a series of three similar gears inclos- 120

ing the rings and corresponding in thickness to the distance between the rings, a spring catch in each gear adjusted at an equiangular distance from the catches in the 5 other two gears, and a case inclosing the three gears and controlling their position; in combination with actuating gearing which is timed to move two of the inclosing gears in opposite directions for a complete 10 revolution while the third gear stands still, and thereafter to move the third gear through a complete revolution while the gears first mentioned stand still; all as set forth.

15 3. In a machine for adjusting bobbin rings which have a spring contact with the bobbin, a pair of enclosing gears, spring catches which react between the gears and the ring joints, and means imparting motion 20 in opposite directions to the two gears for a complete revolution.

4. In a machine for adjusting the open joints of a series of bobbin rings which make frictional contact with their support; the combination of an inclosing gear around 25 each ring a spring catch connecting each gear with its corresponding open joint and means of controlling the motion of the gears which gives to a part of them a complete 30 revolution, while the others are kept from turning in the same direction.

5. In a machine for adjusting the joints of bobbin rings, an adjusting gear, transmission gearing through which approximately one revolution is transmitted to the adjusting 35 gear at a time, a locking cam which moves with the gear, and a swinging arm which adjusts the locking cam to the position from which it started and locks it there.

In testimony whereof I affix my signature.

CLARENCE RAND.
